UNITED STATES PATENT OFFICE.

ABRAHAM LINCOLN KANE, OF MIDDLE FORK, OHIO.

HAY-DERRICK.

SPECIFICATION forming part of Letters Patent No. 380,206, dated March 27, 1888.

Application filed October 5, 1887. Serial No. 251,547. (No model.)

To all whom it may concern:

Be it known that I, ABRAHAM LINCOLN KANE, a citizen of the United States, and a resident of Middle Fork, in the county of

5 Hocking and State of Ohio, have invented certain new and useful Improvements in Hay-Derricks; and I do declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Figure 1 of the drawings is a side elevation of my improved hay-derrick. Fig. 2 is a transverse section of block H. Fig. 3 is a top view of extension-bar i'. Fig. 4 is a transverse section of cap j. Fig. 5 is a vertical longitudinal section of standards C, C', and D, showing slot c.

20 My invention relates to improvements in derricks, especially such as are used in handling hay or straw; and it consists in the construction and novel combination of parts, as hereinafter set forth.

25 Referring to the accompanying drawings, A represents the base-frame of the machine, composed of the beam a and the similar beam, 30 b, secured across the beam a at right angles thereto. (The ends of the beams may be provided with loops or openings through which pins may be driven into the ground to retain the base-frame in place.)

35 C C' are similar standards rising centrally from the beam b, and D is a beam fitting between the standards C C' and rendered adjustable by the longitudinal slot c and the bolts and nuts c', the nuts being provided with handles and the bolts passing through the slot and the openings d in the beam D and the lifting devices, hereinafter described.

40 E is a brace-rod secured at its upper end to the center of the top of the standard C and at its lower end to a pin, F, driven into the ground at a point to the rear of the beam A.

45 e e are brace-rods similar to the brace E, secured at their upper ends to opposite corners of the standard C' and at their lower ends to pins f f, similar to the pin F. The position of 50 the pins F f in the ground forms an equilateral

triangle, so that the frame composed of the beams a b and standards C C' is equally braced in all directions in the well-understood manner.

55

G is a horizontal plate secured to the top of the beam D and provided centrally with the vertical trunnion g, which fits into a corresponding socket in the bearing-block H, the base of which rests on the bearing-plate G, allowing the block to rotate freely on the trunnion. The upper end of said block is bifurcated, and the arms of the bifurcation are provided with journal-bearings h h.

60 I is a working-beam provided on its sides 65 at opposite points with the trunnions i i, which are journaled in the bearings h h. The arm of the working-beam which raises the load has resting upon it a longitudinally-slotted beam, i', which can be moved in or out, so as 70 to extend said arm, and can be secured in its adjusted position by the bolt i'', passing through the slot in the extension and through a suitable opening in the arm.

75 i'' is a chain connecting the beam D below the plate G and the arm of the working-beam near the pivotal point of the latter to limit the upper motion of said arm.

J is a standard rising at right angles from the working-beam between the trunnions, and 80 having the metal cap j secured to its top.

K is a truss or brace rod, which passes through a groove in said cap and has its ends passing through suitable openings or attachments in the opposite arms of the working-beam and tapped therebelow to engage the nuts k k, by means of which the rod K can be tightened and the working-beam more strongly braced.

85 L is a hay-fork of ordinary construction, 90 provided with the tines l l, and connected by the rope or wire M with a hook, m, attached to the arm of the extension-beam i' of the working-beam, which arm stands outward on the same side of the beam D as the brace-rod E. 95

N is a cord attached to the hay-fork, and by means of which a person stacking hay or straw can draw the longer arm of the working-beam to any desired point, and N' is a cord attached to a trigger, n, for the purpose of allowing the tines to drop and release their load.

100 o is a hook secured to the end of the shorter

front arm of the working-beam and supporting a block, O, provided with the sheaf P.

5 p is a rope secured at one end to a staple fixed upon a suitable point on the standard C and passing thence over the sheaf P.

Q is a block provided with a sheaf, q, and a depending stem, r, which is pivoted in a suitable opening in the center of the base.

10 The rope p descends from the sheaf P, passes under the sheaf q, and has the whiffletree S secured to its forwardly-extended end, as shown.

15 It is evident that a horse hitched to the whiffletree, when moving forward, will raise the long rear arm of the working-beam and raise any load that may be attached to the fork, and also that the working-beam, by means of the trunnioned bearing-block, can be swung to any desired horizontal angle.

20 The swiveled block Q permits the line of draft of the rope to correspond with any angle between the braces e e.

T is a rack secured to the side of the beam

D, and U is a lever pivoted to a link, u, which is itself pivoted to one of the side standards, 25 C or C'. By means of the lever and rack the beam can be raised to different heights.

V is a detent pivoted to one of the standards, and v is a spring attached forcing the detent into engagement with the rack.

30 To raise the beam D, the bolts c' must be loosened and tightened again when said beam is adjusted.

Having described my invention, I claim—

35 In a derrick, the combination of the base, the standards C C', the longitudinally-slotted beam D, the set bolts and nuts provided with handles, the rack T, the pivoted lever U, the link u, the detent V, and spring v, substantially as specified.

40 In testimony whereof I affix my signature in presence of two witnesses.

ABRAHAM LINCOLN KANE.

Witnesses:

SAMUEL STEEL,
D. W. JONES.
